END CLOSURE FOR A MULTI-SIDED CARTON

Hans Zerlin, Dusseldorf, Germany, assignor to Jagenberg-Werke Akt.-Ges., Dusseldorf, Germany

Application March 29, 1954, Serial No. 419,441

Claims priority, application Germany May 26, 1953

2 Claims. (Cl. 229—43)

The present invention relates to the art of containers. More particularly, this invention relates to an oil tight container of paper, cardboard or the like carton forming material.

Still more particularly, this invention relates to a polygonal container made of suitable carton forming material that is to receive oil or similarly thinly fluent material, and which container is provided with inserted end closures at one or both ends.

Containers for thinly fluent materials are already known, which are usually manufactured by erecting a generally rectangular blank into a tubular body form with the inner side of the body provided with a moisture proof coating and with the upper and/or lower opening of the container body closed by a closure member preferably made of the same material as the container body. These end closure members correspond in shape to the cross sectional form of the container and are provided at their edges with flanges which will be erected while the closure member is inserted into the open end of the container body to thereby bear against the inner surface of the body at its edges and to be folded down about the external edges of the body so as to enclose the edges in U-shaped formation and to be subsequently compressed to a tight closure about the edges.

In order to provide a liquid or oil tight container of this material, corner staying or sealing presents particular difficulties. For this reason the closure member blanks are formed so that the flanges along the opposite sides thereof are interconnected at their corners with large and substantially triangular shaped sections so that when the flanges are set up these sections connect adjacent flanges of the closure members when the closure is inserted into the carton. Although this arrangement will to a certain extent provide a closed edge at the flanges and therefore a closure that is sufficiently tight for certain goods, it will result in a multiple overlapping of the relatively heavy blank material in the region of the corners of the container. This multiple overlapping tends to form channels or tunnels which will not be closed by any binding agent coated on the inner side of the closure member, since the layer of the binding agent is too thin with respect to the thickness of the material of the closure member blank. Additionally the tunnels will further provide escape channels for seepage and which tunnels due to the thickness of the blank material cannot be closed in the compressing operation applied to the closure member in the securing thereof to the container body.

The present invention, therefore, has for an object to provide a container that is oil tight, that is, leakproof and which eliminates the aforementioned difficulties.

The invention consists in forming the closure member from a blank which is provided with flange forming portions for association internally and externally of the container body and which flange forming portions are formed by cutting out the blank at the corners in com-

2

bination with a leaf of metal foil which only partly or totally covers the inner corner recesses of the closure member blank so that in setting up the flanges and inserting the closure member the portions of the leaf of foil that cover or extend between the corners of adjacent inner flanges on the blank apply themselves around the edges formed by the erected inner flanges. In connection with the invention, the corner recesses or cut outs at the corners of the blank are inwardly limited by the prolongations of the embossed or creased lines or grooves which define the plane of the closure member and the leaf of foil is associated with that side of the closure member facing the interior of the container.

In accordance with the invention, the closure member blank with the corner recesses assumes the function of stiffening the cross sections of the container and for covering and protecting the leaf of foil, while the leaf of foil effects a perfect seal or tightness at the internal corners of the container.

Utilizing the arrangement of the invention, overlappings of relatively stiff or thick blank materials at the corners of the container are eliminated and the thinness of the leaf of foil ensures an effective sealing of the internal corners and encompasses the edges formed by two adjacent inner flanges. Due to the insignificant thickness resulting from any overlapping portions of the foil leaf any tunnels or channels appearing therein will be entirely filled up by a layer of binding material or agent that has been applied to the lower or inner surface of the leaf of foil.

Furthermore, the provision of the foil leaf in association with a closure member blank having completely cut out corners will reduce the pressure required in securing the closure to the container, particularly at the corners thereof, so that the closure can be securely bonded to the container body without any risk of deforming the container material and thus eliminating any necessity to utilize the high pressing power previously used when the closure blank itself was provided with covering portions at the corners of the flanges or flaps and which cover portions had to be folded and refolded to fit within the container and thus provided the multiple overlappings of blank materials.

A further advantage of a container in accordance with the invention consists in the loose superimposition of the surfaces, corresponding to the cross sectional shape of the opening of the container body, of the blank part with the corner recesses on the one hand and of the leaf of foil on the other hand; that is, the foil and container closure blank are not connected together in the major area of the closure. This process presents the advantage, in contradistinction to providing laminated foil materials, that the slight tensile strength of the leaf of foil can follow, free from tension or strain, any deformation of the blank part during insertion of the closure member without being subjected to any particular strain that might damage the foil.

In addition, in accordance with the invention, the blank portions that form the closure member and the leaf of foil are both provided on their sides directed toward the interior of the container with a coating layer that becomes adhesive under the action of heat and pressure, with the foil having the coating layer on its entire inner surface and the closure member being coated only on the flanges. The fact that the blank part is coated only on its flanges, whereas its central panel portion corresponding to the cross sectional shape of the container body is non-adhesive, provides the aforesaid advantages of loose superimposition of the coordinated surfaces of the blank and foil leaf whereby an unintentional adhesion of these elements to each other by the inserting and compressing tools will

be prevented. Furthermore, by not coating the central and large panel of the closure a significant saving and economy in coating material is afforded.

The laminating action formed on the side of the leaf of foil directed toward the interior of the container, with a thermoplastic material such as polyvinyl compositions or other convenient binding agent having simultaneous agglutinate and impregnating properties, will effect, in virtue of these properties, the interconnection of the closure member flanges with the edge of the container body due to the action of heat and pressure and will form at the same time a layer which will reinforce the foil leaf and protect it against the contents of the container. The ratio of thickness of the leaf of foil is such that it is no thicker than the layer of agglutinate so that the channels formed in the sections of foil that overlap each other in the range of the corners of the container are entirely filled up and sealed by the agglutinate agent when it becomes plastic during the application of heat and pressure in sealing the closure to the container body. This results in an absolutely tight connection between the container body and the closure member.

In proceeding in accordance with this invention, the closure blank and leaf of foil are superimposed with the foil between the blank and the container opening. The connection of the foil with the blank will result during insertion and compressing operation, as well as due to the action of heat and pressure, and preferably only in the area of the flanges or flap portions of the blank that bear against the edge of the container body and embrace this edge in U-shaped fashion. Consequently the connection of the leaf of foil with the closure blank part results from the insertion and compression action where, in accordance with the invention, the superimposed central panels of foil and closure member blank corresponding to the cross sectional shape of the opening are not connected with one another, while at the same time, that is, simultaneous with inserting and compressing, the leaf of foil and the finally formed closure member are connected to the edges of the container body.

Therefore, this invention has for an object to provide an end closure for a multi-sided carton in which the internal corners of the carton are adequately sealed and in which all overlapping of blank material forming the closure has been eliminated while still maintaining an effective seal at the corners.

Further and more specific objects will be apparent from the following description taken in connection with the accompanying drawings illustrating one embodiment of the invention and in which:

Figures 1 and 1a respectively illustrate in top plan and with portions removed a flat closure member blank and modified forms of foil leafs disposed thereunder.

Figure 2 illustrates the closure blank of Figure 1 and the underlying leaf of foil still separate therefrom and disposed between the blank and the opening of the container body.

Figure 3 is a partial view illustrating a partially preformed closure member and foil lying against one another and just prior to insertion into the opening of the container body.

Figure 4 is a view similar to Figure 3, but illustrates a further step in which the closure member and foil are preformed to a further extent and partially inserted into the opening of the container body.

Figure 5 illustrates the closure member fully inserted into the container body with the flanges thereof that are to embrace the external edges of the body shown in the position immediately prior to their being sealed to the external surfaces of the body.

Figure 6 is a cross section on an enlarged scale illustrating the structure and connection of an edge of the container body with the closure member, and

Figure 7 is a perspective view illustrating a completed container.

As is clear from Figures 1 and 1a, the closure member that is to be inserted into the open end of a multi-sided tubular carton consists in the blank portions 2 with an underlying leaf of foil 3 separate therefrom. The blank portion 2 is manufactured from a strong material such as cardboard or similar carton forming material or the like, and includes a main body panel 4 corresponding in shape to the cross sectional form of the container body opening which, in the example illustrated, is rectangular. The closure member blank further includes flanges 7 and 8 that are interconnected therewith and defined by creased or embossed grooves 5 and 6 which constitute fold lines. The prolongations of the grooves 5 beyond their contacting points define the lengths of flanges 7 and 8 and thus 15 the substantially rectangular corner recesses 9 of the blank. The invention further has the outer flanges 8 slightly longer than the inner flanges 7 so that the flanges 8 when folded down over the upper edges of the carton container 1 close the edge of the container and thus form a closed edges as shown in Figure 7.

The leaf of foil 3, which may be manufactured of metal such as aluminum, cellulose, plastic or other suitable material, corresponds in substance to the external dimensions of the blank part 2 with the sole difference that instead of having its corners cut out as at 9 on the blank these corner recesses are partly covered by foil material. These covering sections of foil may be sector shaped, as shown at 10 in Figure 1, or define triangles, as shown at 10' in Figure 1a. Obviously any suitable shape can be provided so long as the foil leaf is formed such that the area thereof underlying the flange forming portions 7 are at least partially filled at the corners of the foil. As shown in Figure 6, the side of the foil leaf that is directed toward the interior of the container body 30 is provided on its whole surface with a coating layer 11 of a material that becomes adhesive under the action of heat and pressure. The thickness of this coating layer 11 corresponds to the thickness of the leaf of foil 3. An equal layer of coating material 12, that is, equal in thickness and having the same adhesive qualities, is applied to the under surface of the flange forming portions 7 and 8 of the closure blank part 2. Since the under surface of panel 4 of the closure blank is not coated the foil is not laminated or connected to this panel 4.

The container body 1 is also provided or lined with a leaf of foil 14 carrying a layer of coating material 13 on the outer surface thereof. The leaf of foil 14 is firmly connected by adhesive or the like, not shown, to the interior surface of the container body after taking into account the fact that the container body is not exposed to any deformation during manufacture so that there is no danger of deteriorating the leaf of foil 14. The invention thus provides an arrangement in which a container has a closure inserted in the end thereof and which closure includes a planar body portion and U-shaped flange portions respectively separate from one another and corresponding in length to the respective inner and outer dimensions of the upper edges of the container body and provided with a foil lining that includes portions adhesively secured to the flanges on the inner and outer surfaces of the container body and portions adhesively secured to one another and overlapping the corner joints of the flanges at the internal corners of the container.

The different steps of forming the end closure and thus closing and sealing a carton are illustrated in Figures 2 to 5, in which is shown that the closure blank 2 with its underlying leaf of foil is first disposed above and adjacent the open end of the container body (Figure 2). With the motion of the blank part 2 and the leaf of foil 3 toward the container body, as shown by the arrow, the connection of the leaf of foil to the blank will be effected in partially setting up flanges 7 and 8 around the embossed lines 5, as shown in Figure 3. With continued movement and further setting up of flanges 7

and 8 and introduction of the thus set up closure consisting of combined blank 2 and foil 3 into the container body 1, as shown in Figure 4, the sections 10 or 10' of the leaf of foil that cover the corner recesses 9 of the closure blank 2 will take the form of outwardly buckled web portions 10''. In the subsequent inserting movement these web portions will embrace the edges of the set up closure blank between the internal side of the container body 1 and the flanges 7 of the closure member 2 and flanges 7' of the foil leaf. The combined closure member 2 and foil 3 inserted into the container body down to the score line 6 will be completed by folding down flanges 8 around the edges of the container body 1, as shown in Figure 5, and the foil flanges 7' that underlie the flanges 8 are adhesively secured thereto under the action of heat and pressure established by the conventional reciprocable sealing tools. In this operation layer 12 becomes plastic and connects the flanges 7 and 8 of the blank 2 with the flange forming portion of the leaf of foil 3 and the coating layer 11. The coating layer 11 is also secured to the coating layer 13 on the interior of the container body and to the exterior of the container body in that portion crossing the top edge of the container and underlying the flange 8. As previously described, since the flanges 8 of the container closure blank are longer than flanges 7 the adjacent edges of flanges 8 will meet at the exterior corners of the container to form a tight external corner closure. Further, the flanges 7 will provide rigidity in the transverse direction on the interior of the container, and the web portions 10'' will securely seal the interior corners of the container since the thinness of the leaf of foil will permit adequate compressing of foil into the corners with any channels or tunnels formed therein being filled and sealed by the adhesive layer 11 which becomes soft during the process of sealing.

It is to be pointed out that this invention comprehends the superimposition of a closure blank having free flange forming portions extending from each side over a foil element that at least extends between adjacent side edges of the adjacent flange forming portions and inserting the superimposed blank and foil element or elements into the open end of the container to fold up the flange forming portions and wedge or compress the foil into the inner corners of the container to seal these inner corners.

It is to be further understood that this invention is not

to be limited to an arrangement in which a complete leaf of foil underlies the entire closure blank since an effective corner seal will result from the provision of a leaf of foil underlying the corner recesses of the blank part, as at 9, and at least extending partially along the under surfaces of blank forming portions 7 and 8.

What is claimed is:

1. In a leakproof container of paper, cardboard or like carton forming material, a body including side walls and a rim, said side walls defining a multi-cornered construction, a closure for at least one end of the body including a main closure panel having free flanges extending therefrom, said flanges corresponding in number and transverse extent to the number and transverse extent of the side walls of the body and being substantially at right angles to the main panel and extending away therefrom a distance at least sufficient to be opposed to the inner surfaces of the side walls so that the main panel lies inwardly of the rim of the body, a lining sheet arranged interiorly of the main closure panel and including uninterrupted perimetrical portions secured to the flanges and the adjacent inner surfaces of the side walls, and said perimetrical portions including web portions in the interior corners of the body embracing only the adjacent inner edges of the flanges at each inner corner and extending axially of the container only between the corners formed by adjacent inner flanges and the respective interior corners of the container.
2. A leakproof container as claimed in claim 1 in which said lining sheet is a foil lining sheet and includes a main body portion underlying the main panel of the closure and free of positive connection thereto.
